UNITED STATES PATENT OFFICE.

ARNOLD S. BERTELS, OF TENAFLY, NEW JERSEY, ASSIGNOR TO WESTERN ELECTRIC COMPANY, INCORPORATED, OF NEW YORK, N. Y., A CORPORATION OF NEW YORK.

TESTING DEVICE FOR TELEPHONE-EXCHANGE SYSTEMS.

Application filed November 6, 1922. Serial No. 599,229.

To all whom it may concern:

Be it known that I, ARNOLD S. BERTELS, a citizen of the United States of America, residing at Tenafly, in the county of Bergen and State of New Jersey, have invented certain new and useful Improvements in Testing Devices for Telephone-Exchange Systems, of which the following is a full, clear, concise, and exact description.

- 10 This invention relates to a telephone exchange system, and more particularly to testing circuits for use therein in testing call indicator trunks and call indicator circuits.
- 15 In a telephone exchange system during the period when the exchange is being changed from a manual to an automatic operating basis, there are certain offices which are equipped with machine switching
- 20 apparatus and function for calls local thereto on a full mechanical basis, and other offices which temporarily are equipped only with regular manual equipment. In certain exchange areas there may also be offices
- 25 which for certain traffic reasons it may not be desirable or economical to change from manual to machine switching equipment. Such manual offices, in order that connections originating in machine switching offices may be terminated therein, are equipped with operators' positions in which appear trunks incoming from all machine switching offices having access thereto. Each such operator's position is also equipped with a
- 30 call indicator mechanism upon which may be recorded, under the control of the calling subscriber in the originating office, the number of the line desired in such terminating manual office. Call indicator mechanism of
- 35 this character is well known in the art and may be of the type disclosed, for example, in the patent to A. E. Lundell and Edgar H. Clarke No. 1,464,084, issued August 7, 1923.
- 40 In order that at all times the call indicator trunks incoming to a manual office and the call indicator mechanism associated therewith shall be maintained at the highest possible degree of efficiency, it is desirable that means be provided for making special and routine tests of such trunks and mechanism from time to time. It is

therefore the object of the present invention to provide testing mechanism and circuits for making special or routine tests of any 55 trunk circuit or call indicator mechanism of a manual office of the character above described.

The principal feature of the invention resides in the provision of a portable test box 60 which may be connected at will by cord circuits to any call indicator trunk circuit or to any call indicator mechanism of an office, and which is provided with a keyboard upon which any line designation 65 may be recorded, and an impulsing switch for simulating the operation of the impulsing switch of a regular office sender whereby the control circuits and indicator lamps 70 are caused to function in the standard manner to indicate the recorded designation.

A further feature of the invention resides in the provision of means in the test box for testing the operation and adjustment of certain relays of control circuits or trunk 75 circuits under test simulating the best and worst conditions under which such relays must operate in actual service.

A further feature resides in the provision of means for transmitting individual impulses of light or heavy positive and negative current for testing the sensitive and marginal relays of a call indicator control circuit.

A still further feature resides in the provision of circuits for testing the accuracy with which the call indicator control circuit and trunk circuit under test function in the selection, application and tripping of ringing current when applied to call a particular party on a party line.

These and other features of the invention will be more apparent from a consideration of the following description and appended claims.

Referring to the drawings, Figs. 1 to 6, inclusive, when arranged in the order illustrated in Fig. 7, disclose so much of the circuits of a manual call indicator operator's apparatus and of the testing device which embodies the invention as is necessary to an understanding of the invention.

Fig. 1 shows a test line to which connection may be established by any call in-

dicator trunk of the manual office, such as the trunk of Fig. 2, having ringers similar to the ringers of a four party subscriber's line, together with jacks and patching cords for enabling connections to be established between the testing device of Figs. 3 and 4 and the control circuit of Fig. 5, or between the testing device and the testing line and trunk circuit of Figs. 1 and 2.

10 Fig. 2 shows a call indicator trunk circuit incoming from a machine switching office for extending connections to subscribers' lines and arranged to cooperate with the call indicator disclosed in Figs. 5 and 6.

15 Figs. 3 and 4 taken together show the circuits of a portable testing device for making tests of call indicator circuits, such as shown in Fig. 2, or call indicator mechanism, such as shown in Figs. 5 and 6. Fig. 20 Fig. 3 shows the keyboard of the testing device, and Fig. 4 shows the impulsing switch, controlling relays, keys and lamp signals of the testing device.

25 Fig. 5 shows the control circuits of a call indicator mechanism arranged to be associated with any of the trunk circuits, such as shown in Fig. 2, of an operator's position, and operative in response to code impulses transmitted thereto over a trunk circuit incoming from a machine switching office or from the testing device of Figs. 3 and 4.

30 Fig. 6 shows the selecting relays and numerical lamps of the call indicator for visually informing the manual operator of the designation of the called line.

General description of circuits and apparatus.

35 The call indicator trunk circuit of Fig. 2 and the call indicator mechanism shown in Figs. 5 and 6 are of the same general type as disclosed in the aforesaid patent, differing therefrom only in the provision of means for selecting and applying ringing current 40 to the calling strands of the trunk circuit in accordance with the designation of the party line station, indicated by the stations lamps on the call indicator, and in the provision of an additional marginal relay in the impulsing circuit of Fig. 5. Two marginal 45 control relays are provided in order that the call indicator may be employed with trunk circuits of two groups, the trunk circuits of one of said groups having loop resistances within certain specified limits, over which 50 one of said marginal relays is adjusted to function, and the trunk circuits of the other of such groups having loop resistances within other specified limits, over which the 55 other of said marginal relays is adjusted to function.

60 The keys of the keyboard, shown in Fig. 3, with the exception of keys 300, 308 and 309, are of the mechanically locking type, the key in any vertical row being maintained

operated until restored by the depression of another key in the same row. The sequence switch, the cams of which are shown at the left of Fig. 4, may be of the general type shown in the patent to J. N. Reynolds and C. F. Baldwin No. 1,127,808, issued February 9, 1915, differing therefrom only in that the cams thereof are operated by a manually wound spring motor which is released to permit a single revolution of the switch through the operation of the release magnet 400. The provision of a spring driven sequence switch is essential because of the fact that the test box must be portable and that it is designed to be employed in manual offices 75 which are not equipped with power equipment of the machine switching type. The switch 450, shown at the right of Fig. 4, may be of the type disclosed in the patent to G. Brown No. 1,155,640, issued October 5, 1915, 80 being driven by a spring motor, which when wound up and released, causes a single revolution of the cams thereof.

85 The testing device of Figs. 3 and 4, as previously mentioned, may be employed for 90 conducting two types of tests. When it is desired to test a call indicator mechanism, such for example, as that shown in Figs. 5 and 6, the jacks of the testing device 100, 103 and 104 are connected by cord circuits, 95 known as patching cords, 105, 108 and 109 to jacks 110, 111 and 112, respectively, individual to the call indicator to be tested, and the jacks 101 and 102 of the testing device by patching cords 106 and 107 to power 100 jacks 114 and 115. Following the connection of the testing device to the indicator mechanism, the spring driven sequence switch is wound up, the designation of the first test number is recorded upon the keys of the keyboard, and the start key 300 is operated. The sequence switch upon being released through the operation of the start key transmits the proper code of impulses to selectively light the lamps of the indicator in accordance with the designation recorded on the 105 keyboard. In this manner the test man may check the accuracy of operation of the indicator by noting the designation recorded by the depressed keys of the keyboard and by 110 the lamps which are lighted at the call indicator mechanism. If the first test call is successively indicated, another test call with the same designation is made, but under different circuit conditions. If the indicator 115 functions properly the designation of the next test number is recorded and the testing operations are repeated. In this manner twenty test calls are established with ten different designations. It will be noted by 120 reference to the following table that the digits of the test numbers are so selected that the control circuit and lamp relays of the indicator under test are operated in all possible 125 combinations.

Table of test call numbers.

	Th.	H.	T.	U.	Sta.
5 (1)	0	1	2	3	O
(2)	1	2	3	4	R
(3)	2	3	4	5	J
(4)	3	4	5	6	R
(5)	4	5	6	7	M
(6)	5	6	7	8	W
(7)	6	7	8	9	O
(8)	7	8	9	0	R
10 (9)	8	9	0	1	J
(10)	9	0	1	2	R

Should it be desired to test a trunk circuit, such as shown in Fig. 2, the jacks 100 to 104, inclusive, are connected by patching cords 105 to 109, inclusive, to jacks 113 to 117, inclusive. The spring driven sequence switch is wound up, the designation 00000 is set up on the keyboard, and the starting key 100 depressed. The testing device then functions in the same manner as above set forth to operate the trunk circuit to which the testing device is connected and the indicating mechanism associated therewith in the same manner as they would be operated upon a call incoming thereto from a machine switching office. When the operator assigns the trunk to her indicator by depressing the assignment key 211, the impulsing switch of the testing device is released, and transmits to the call indicator associated with the trunk circuit impulses for setting the indicator in accordance with the designation set up on the keyboard of the testing device. This designation being 00000, the operator knowing that this designation indicates that the call has come to her trunk circuit from the testing device, plugs into the jack 227 of the test line. Upon the connection of the trunk circuit with the test line, ringing current is selectively applied thereto to ring one of the bells associated with the test line, whereupon the test man may proceed to make whatever tests are necessary in connection with the apparatus of the trunk circuit under test. Should the test man desire to test the trunk circuit for applying ringing current necessary for ringing any one of the four bells of a party line, he may do so by successively setting up numbers on the keyboard, each number comprising four numerical digits O and a different station digit, either J, R, M or W.

55 Testing a call indicator mechanism.

It will be assumed that the test man desires to test the call indicator mechanism disclosed to Figs. 5 and 6, and for that purpose connects the jacks 100 to 104, inclusive, with jacks 110, 114, 115, 111 and 112 by the cords 105 to 109, inclusive, and disconnects all incoming trunks at the operator's position with which the call indicator mechanism is associated from the call indicator to be tested, and connects such trunks to the

emergency equipment so that all calls which may come in to the operator's position during the test may be handled by the emergency equipment without tying up the operator's position.

For the purpose of this description it will be assumed that the marginal relay 500 of the call indicator is adjusted to operate over interoffice trunk loops of 2100 to 2600 ohms resistance, and that the marginal relay 501 is adjusted to operate over loops of 800 to 1700 ohms resistance, and that the indicator mechanism is to be tested first with relay 500, key 401 of the testing device being for this purpose in its normal position. The test man thereupon depresses the key 302 for inserting the lowest voltage and the highest resistance into the impulse circuit extending from the testing device to the call indicator mechanism, in series with marginal relay 500, for simulating the worst operating condition under which the marginal relay 500 would be designed to operate in actual service. The test man thereupon depresses the thousands key 303, the hundreds key 304, the tens key 305, the units key 306 and the stations key 307 for recording upon the keyboard the designation of the first test number appearing in the aforementioned table, 01230, and winds the motor of the spring driven sequence switch. This sequence switch is restrained from returning to normal by the detent on the armature of magnet 400. The circuits of the testing device are now in condition for making the first test, and the test man thereupon depresses the start key 300.

With the start key 300 depressed and the trunk testing key 402 and disconnect keys 308 and 309 in normal position, a circuit is established for relay 403 of the testing device and relay 502 of the indicator under test, which may be traced from battery, through the winding of relay 502, conductor 503, sleeve of jack 111, sleeve strand of cord 108, sleeve of jack 103, conductor 118, the normal contact of spring 404 of key 402, conductor 405, the right contact of key 308, conductor 310, the left winding of relay 403, conductor 406, the right contact of key 300, conductor 311, the normal contact of spring 407 of key 402, conductor 408, ring of jack 103, ring strand of cord 108, ring of jack 111, conductor 119, and thence to ground by parallel paths, one extending through the winding of relay 504 and the other through the normal contact of relay 505, conductor 506, to ground at the left armature and contact of relay 507. Relay 504 being shunted at this time by direct ground at the contact of relay 507 does not energize, but relays 403 and 502 energize. Relay 502, upon energizing, connects ground to the holding conductors 508 and 509 through the armature contacts of relay 510 for furnishing operating

and locking ground for the various relays of the indicator mechanism, as will appear hereinafter. Relay 403, upon energizing, locks through both of its windings over a 5 circuit from ground at the normal contact of spring 409 of key 402, conductor 410, the inner right armature and front contact of relay 403, thence through both windings of relay 403 and over the circuit previously 10 traced to battery through the winding of relay 502. Relay 403 is thus maintained energized in series with relay 502 independent of start key 300, which may now be released. 15 Relay 403 also closes a circuit for relay 411 in series with relay 505, which may be traced from battery through the winding of relay 411, conductor 412, the left armature and contact of relay 403, the outer right armature and contact of relay 413, the 20 normal contact of spring 414 of key 402, conductor 415, the tip of jack 103, the tip strand of cord 108, the tip of jack 111, conductor 120, winding of relay 505, the ground at the right armature and back contact of 25 relay 507. Relay 505, upon energizing, opens the shunt around relay 504 and relay 411 closes a circuit for the sequence switch release magnet 400, which latter circuit may be traced from battery, through the winding 30 of release magnet 400, the normal contact of key 416, the intermediate armature and front contact of relay 411, the right contacts of cam 417 (1), the left armature and back contact of relay 418, conductor 419, and thence to ground through the left 35 contacts of keys 308 and 309. Relay 411 also establishes an impulse circuit from the cams of the sequence switch to the control circuit of the call indicator mechanism, 40 which will be traced hereinafter in connection with the transmission of code impulses of the first test number. The removal of the shunt from around relay 504 is without function at this time, since upon the release of start key 300, the circuit previously 45 traced through the winding of relay 504 is open at the contacts of key 300.

It has been assumed that the stations digit of the first test number was 0, and that the 50 No. 0 stations key 307 was depressed. It will be noted from an inspection of this key that its contacts are without function, and that therefore during the revolution of the sequence switch of the testing device, the impulsive circuit is unmodified while it is rotating from position 1 through position 3 and through position $4\frac{1}{2}$, and that therefore light negative impulses are transmitted over the impulse circuit only in positions $3\frac{3}{4}$ and 55 $5\frac{1}{4}$. When, therefore, the sequence switch reaches position $3\frac{3}{4}$, a circuit is established which may be traced from ground at the ring contact of jack 114, the ring strand of cord 106, the ring contact of jack 101, conductor 121, the upper contact of sequence 60

switch cam 420 ($3\frac{3}{4}$), the outer left armature and front contact of relay 411, conductor 421, the left armature and back contact of relay 413, conductor 422, the tip of jack 104, tip strand of cord 109, tip of jack 112, conductor 122, inner right armature and back contact of relay 511, conductor 512, winding of positively polarized relay 513, winding of negative polarized relay 514, winding of marginal relay 500, conductor 515, outer left armature and back contact of relay 511, conductor 516, ring of jack 112, ring strand of cord 109, ring of jack 104, conductor 123, normal contact of key 401, conductor 423, resistance elements 312 to 318, inclusive, left contact of key 302, conductor 319, normal contact of key 320, conductors 321 and 424, right armature and front contact of relay 411, upper contact of sequence switch cam 425 ($3\frac{3}{4}$), high resistance element 426, conductor 427, ring of jack 102, ring strand of cord 107, ring of jack 115, left armature and front contact of relay 124 to 45 volt battery 126 through the armature and back contact of relay 125. It is to be noted that at this time relay 124 is energized over a circuit extending from battery, through its winding, the sleeve of jack 115, sleeve strand of cord 107, sleeve of jack 102, to ground. 95

The current flowing over the circuit previously traced through the high resistance 100 426 is therefore of light strength and of negative polarity, causing only the energization of the negatively polarized relay 514, relay 500 not receiving sufficient current to cause its energization. Since at this time relay 502 is energized and has connected ground to conductor 509, a circuit is established from ground on conductor 509 105 through the armature contact of relay 514, the normal contacts associated with the inner left armature of relay 511, the left armature and back contact of relay 517, winding of relay 518, to battery through the left winding of relay 517. Relay 518 energizes in this circuit, but relay 517 does not receive sufficient current to cause its 110 energization. Relay 518, upon energizing, closes a circuit from battery, through the left winding of relay 517, the winding of relay 518, the right winding of relay 517, the right armature and front contact of relay 518, to ground on conductor 509. Relay 517, however, does not energize 115 at this time since its right hand winding is shunted through the contact of relay 514. Relay 518 at its right armature and front contact also closes a circuit for transfer relay 519, which may be traced from battery, through the winding of relay 519, left armature and back contact of relay 520, right armature and front contact of relay 518 to ground on conductor 509. Relay 519, upon attracting its armatures, establishes a locking 120 125 130

circuit for itself from battery, through its winding, the winding of relay 520, the right armature and contact of relay 519, to ground on conductor 509. Relay 520, however, does not energize at this time since its winding is shunted by a direct path to ground, through the contact of relay 518. As soon, however, as the sequence switch of the testing device leaves position $3\frac{3}{4}$, relay 514 releases and removes the shunt from around the right winding of relay 517, whereupon relay 517 energizes in series with relay 518.

While the sequence switch passes through position $5\frac{1}{4}$, the circuit through relays 500, 513 and 514 previously traced is again closed, and relay 514 again energizes and upon attracting its armature, closes a circuit from battery, through the left winding of relay 517, left armature and front contact of relay 517, normal contacts associated with the inner left armature of relay 511, contact of relay 514, to ground on conductor 509. This direct circuit to ground shunts the winding of relay 518, causing it to de-energize and release its armatures. Upon the release of its right armature, the shunt around the winding of relay 520 is opened, but this relay is still maintained shunted over the inner right armature and front contact of relay 517. When the sequence switch moves out of position $5\frac{1}{4}$, relay 514 releases its armature and opens the circuit through the left winding of relay 517. Relay 518 being at this time deenergized, no other circuit exists for relay 517, and consequently this relay becomes deenergized. When relay 517 releases its armatures the shunt around the winding of relay 520 is removed and this relay energizes in series with relay 519. It will be noted that none of the stations relays 521 to 525, inclusive, have been operated.

Since the thousands digit of the first test number is also 0, and as the No. 0 thousands key 303, which has been depressed, has no effective contacts, the impulsing circuit controlled by the sequence switch is unmodified as it rotates from position $5\frac{1}{4}$ through position 6 and from position $6\frac{3}{4}$ through position $7\frac{1}{2}$, therefore as it passes positions $6\frac{3}{4}$ and $8\frac{1}{4}$ light negative current is supplied to the impulse circuit above traced. As the sequence switch passes through position $6\frac{3}{4}$, relay 514 energizes and causes the operation of relay 518 in the manner previously described. Relay 518 prepares an energizing circuit for relay 517 and establishes a circuit for transfer relay 526 which may be traced from battery, through the winding of relay 526, the left armature and back contact of relay 527, left armature and front contact of relay 520, the right armature and front contact of relay 518, to ground on conductor 509. Relay 526, upon

energizing, closes a locking circuit for itself extending through its winding, the winding of relay 527, the inner right armature and contact of relay 526, to ground on conductor 509, but relay 507 being shunted at this time through contacts of relay 518 does not energize in this locking circuit. When the sequence switch leaves position $6\frac{3}{4}$, relay 514 deenergizes and removes the shunt from around the right winding of relay 517, whereupon relay 517 energizes in series with relay 518.

As the sequence switch passes through position $8\frac{1}{4}$, relay 514 again energizes and establishes the previously traced circuit through the left winding of relay 517, whereupon relay 518 being shunted, deenergizes. As soon as the sequence switch leaves position $8\frac{1}{4}$, relay 514 again deenergizes, opening the holding circuit of relay 517 and causing its deenergization. Since at this time relay 518 is deenergized, the winding of relay 527 is no longer shunted and this relay energizes in the locking circuit of relay 526. As two light negative impulses have been transmitted to the indicator mechanism, it will be noted that none of the thousands lamp relays 600 to 603, inclusive, have been operated.

When the sequence switch of the testing device reaches position 9 with the No. 1 hundreds key 304 depressed, an impulse of positive current is transmitted through the windings of relays 500, 513 and 514 over a circuit which may be traced from the non-grounded pole of battery 126, the armature and back contact of relay 125, the left armature and front contact of relay 124, ring of jack 115, ring strand of cord 107, ring of jack 102, conductor 427, resistance 429, resistance 428, upper contact of cam 430 (9 to $10\frac{3}{4}$), upper contact of cam 431 ($8\frac{3}{4}$ to 11), conductor 432, right contact of key 304, conductors 322 and 323, the upper contact of cam 433 ($8\frac{3}{4}$ to $9\frac{1}{2}$), the lower contact of cam 433 (9), the outer left armature and front contact of relay 411, conductor 421, left armature and back contact of relay 413, conductor 422, tip of jack 104, tip strand of cord 109, tip of jack 112, conductor 122, inner right armature and back contact of relay 511, conductor 512, windings of relays 513, 514 and 500, conductor 515, outer left armature and back contact of relay 511, conductor 516, ring of jack 112, ring strand of cord 109, ring of jack 104, conductor 123, normal contact of key 401, conductor 423, resistances 312 to 318, inclusive, left contact of key 302, conductor 319, contact of key 320, conductors 321 and 424, right armature and front contact of relay 411, lower contact of cam 420 (9), conductor 121, ring of jack 101, ring strand of cord 106, ring of jack 114, to ground. Due to the inclusion of the high resistance 428, a weak impulse of

current of the proper polarity is transmitted, and only the positively polarized relay 513 energizes. Relay 513 completes a circuit from the grounded conductor 509, 5 armature and contact of relay 513, left armature and back contact of relay 518, left armature and front contact of relay 519, left armature and front contact of relay 526, outer left armature and back contact 10 of relay 528, conductor 530, left winding of hundreds lamp relay 604, to battery. Relay 604 becomes energized and closes a holding circuit for itself from battery, through its two windings in series, contact and inner 15 right armature of said relay, to grounded conductor 508. As the sequence switch leaves position 9, the impulse circuit is opened and relay 513 deenergizes.

As the sequence switch passes through position 9 $\frac{3}{4}$, it closes a circuit from the non-grounded pole of battery 126 as previously traced through resistance 426, upper contact of cam 425 (9 $\frac{3}{4}$), the right armature and front contact of relay 411, thence as 20 previously traced through the windings of relay 500, 513 and 514, outer left armature and front contact of relay 411, the upper contact of cam 420 (9 $\frac{3}{4}$), and as previously 25 traced to ground at jack 114. A weak impulse of current is thus sent in this circuit of the proper polarity to energize relay 514. Relay 514 closes the energizing circuit for relay 518 as previously described, relay 517 remaining deenergized. Relay 518, upon 30 energizing, completes a circuit from battery, through the winding of relay 528, left armature and back contact of relay 529, the left armatures and front contacts of relays 527 and 520, the right armature and front 35 contact of relay 518, to ground on conductor 509. Relay 528 attracts its armatures and completes a circuit from battery, through the windings of relays 528 and 529 in series, front contact and inner right armature of 40 relay 528, to grounded conductor 509. Relay 529, however, does not energize since its winding is shunted by the contacts of relay 518. As the sequence switch leaves position 9 $\frac{3}{4}$, the impulse circuit above traced is 45 opened and relay 514 deenergizes to permit the energization of relay 517 in series with relay 518.

As the sequence switch passes through position 11 $\frac{1}{4}$, a circuit is again closed through 50 the windings of relays 500, 513 and 514, through the upper contacts of cams 420 and 425, and a weak impulse of current is transmitted of the proper polarity to again cause the energization of polarized relay 514. Relay 514, upon energizing, closes a short circuit around the winding of relay 518, causing this latter relay to release. As the sequence switch moves out of position 11 $\frac{1}{4}$, relay 514 releases its armature to permit the deenergization of relay 517. When relay

517 becomes deenergized, the short circuit which up to this time has been maintained around the winding of relay 529 is removed. Relay 529 thereupon energizes and locks in series with relay 528. At the time relay 528 70 energized, a circuit was established for the 0 stations lamp 531, it being recalled that none of the stations lamp relays were operated as the result of the transmission of the stations code of impulses. This circuit 75 may be traced from battery, lamp 531, outer left armature and back contact of relay 521, inner left armature and back contacts of relays 523, 524 and 525, conductor 532, to ground at the inner left armature and front 80 contact of relay 528.

As the sequence switch passes through position 12 $\frac{3}{4}$, since at this time the No. 2 tens key 305 is depressed, a circuit is effective 85 for relays 500, 513 and 514, which may be traced from the non-grounded pole of battery 126, thence as previously described through low resistance 429, the lower contact of cam 430 (12 $\frac{3}{4}$ to 13), the lower contact of cam 434 (11 $\frac{3}{4}$ to 14), conductor 435, right 90 contact of key 305, conductors 324 and 325, contacts of cam 425, thence over the circuit previously traced through the windings of relays 500, 513 and 514 to the outer left 95 armature and front contact of relay 411, the upper contact of cam 420 (12 $\frac{3}{4}$), to ground at jack 114. The impulse of current transmitted in this circuit is strong in character since only the low resistance 429 is included, both high resistances 426 and 428 being excluded, and therefore causes the energization 100 of marginal relay 500. Further, the polarity of the impulse is such as to cause the energization of relay 514. Relay 514 attracts its armature and closes the circuit described for the energization of relay 518. Relay 518 in turn closes a circuit from battery, through the winding of transfer relay 533, the left armature and back contact of 105 relay 534, the left armatures and front contacts of relays 529, 527 and 520, right armature and front contact of relay 518, to grounded conductor 509. Relay 533 energizes and closes a locking circuit for itself 110 extending through its winding, the winding of relay 534, the inner right armature and front contact of relay 533, to grounded conductor 509. Relay 534 does not energize, 115 however, as long as either of the relays 517 or 518 is operated. Relay 500 completes a 120 circuit from grounded conductor 509, armature and contact of relay 500, outer right armature and back contact of relay 517, inner right armatures and front contacts of 125 relays 520, 527 and 529, inner right armature and back contact of relay 534, conductor 535, left winding of the tens lamp relay 609, to battery. Relay 609 energizes and locks in a circuit from battery with both its windings in series, its inner right armature 130

and front contact, to ground on conductor 508. As the sequence switch leaves position $13\frac{3}{4}$, the impulse circuit is opened and relays 500 and 514 become deenergized. Relay 514 now removes the shunt from around the winding of relay 517, permitting this relay to become energized in series with relay 518.

The sequence switch in moving through position $14\frac{1}{4}$ again closes a circuit through relays 500, 513 and 514 from the non-grounded pole of battery 126, as previously traced through resistance 426, the upper contact of cam 425 ($14\frac{1}{4}$), the right armature and front contact of relay 411, thence as traced through the windings of relays 500, 513 and 514, to the outer left armature and front contact of relay 411, the upper contact of cam 420 ($14\frac{1}{4}$), thence as previously traced to ground at jack 114. Since resistance 426 is included in this circuit, a weak impulse is therefore transmitted of the polarity necessary to cause the energization of relay 514. Relay 514 closes a shunt circuit for causing the deenergization of relay 518. In moving out of position $14\frac{1}{4}$, the sequence switch opens the impulse circuit and relay 514 releases permitting the release of relay 517. Relay 517 and relay 518 now both being deenergized, the shunt around the winding of relay 534 is removed and this relay energizes in the locking circuit of relay 533.

As the sequence switch passes through position 15 with the No. 3 units key 306 depressed, a circuit is established for relays 500, 513 and 514, which may be traced from the non-grounded pole of battery 126, as previously described, through the low resistance 429, resistance 428, the upper contact of cam 430 (15 to $16\frac{3}{4}$), the upper contact of cam 434 ($14\frac{3}{4}$ to 17), conductor 436, the right contact of key 306, conductors 326 and 327, lower contact of cam 437 (15), thence over the circuit previously traced through the windings of relays 500, 513 and 514, returning through the lower contact of cam 420 (15), to ground at jack 114. Due to the inclusion of high resistance 428, a weak impulse of current is transmitted and only the positively polarized relay 513 energizes. Relay 513 completes a circuit from grounded conductor 509, armature and contact of relay 513, left armature and back contact of relay 518, left armatures and front contacts of relays 519 and 526, outer left hand armatures and front contacts of relays 528 and 533, conductor 536, left winding of units lamp relay 612 to battery. Relay 612, upon energizing, closes a holding circuit for itself from battery, through its two windings in series, its inner right armature and contact, to grounded conductor 508. As the sequence switch leaves posi-

tion 15, the impulse circuit is opened and relay 518 deenergizes.

The sequence switch in passing through position $15\frac{3}{4}$ closes a circuit through relays 500, 513 and 514, which may be traced from the non-grounded pole of battery 126, thence as previously described through low resistance 429, the lower contact of cam 430 ($15\frac{3}{4}$ to 16), the upper contact of cam 434 ($14\frac{3}{4}$ to 17), conductor 436, right contact of key 306, conductors 326 and 327, the upper contact of cam 437 ($15\frac{3}{4}$), thence as previously traced through the windings of relays 500, 513 and 514, returning over the upper contact of cam 420 ($15\frac{3}{4}$) to ground at jack 114. The impulse of current transmitted in this circuit is strong in character since only the low resistance 429 is included, and resistances 426 and 428 are both excluded, and therefore causes the energization of marginal relay 500. Further, the polarity of the impulse is such as to cause the energization of relay 514. Relay 514 attracts its armature and closes the circuit previously described for energizing relay 518. Relay 518 in turn closes a circuit from battery, through the winding of transfer relay 537, left armatures and front contacts of relays 534, 529, 527 and 520, the right armature and contact of relay 518, to grounded conductor 509. Relay 537 energizes and closes a locking circuit for itself extending through its winding, winding of relay 511 and the inner right armature and contact of relay 537, to grounded conductor 509. Relay 511 does not energize, however, as long as either of the relays 517 or 518 is operated. Relay 500 completes a circuit from grounded conductor 509, armature and contact of relay 500, outer right armature and back contact of relay 517, inner right armatures and front contacts of relays 520, 527, 529 and 534, conductor 538, to battery through the left winding of units lamp relay 613. Relay 613 energizes and locks in a circuit from battery, through both of its windings in series, its inner right armature and contact, to ground on conductor 508. As the sequence switch leaves position $15\frac{3}{4}$, the impulse circuit is opened and relays 500 and 514 become deenergized. Relay 514 upon deenergizing, removes the shunt from around the winding of relay 517, permitting this relay to become energized in series with relay 518.

The sequence switch in moving through position $17\frac{1}{4}$ again closes the circuit through relays 500, 513 and 514 from the non-grounded pole of battery 126, thence as previously traced through resistance 426, upper contact of cam 425 ($17\frac{1}{4}$), the right armature and front contact of relay 411, thence as traced through the windings of relays 500, 513 and 514, returning through the

outer left armature and front contact of relay 411, the upper contact of cam 420 (17 $\frac{1}{4}$), thence to ground at jack 114. As the resistance 426 is included in this circuit, 5 a weak impulse is therefore transmitted of the polarity necessary to cause the energization of relay 514. Relay 514 closes a shunt circuit for causing the deenergization of relay 518 in the manner previously described. 10 In moving out of position 17 $\frac{1}{4}$, the sequence switch opens the impulse circuit and relay 514 releases, permitting the release of relay 517. Relays 517 and 518, now both being deenergized, the shunt around the winding of 15 relay 511 is removed, and this relay energizes in the locking circuit of relay 537. The lamp relays 604, 609, 612 and 613 have now been energized preparatory to causing the display of the test number 0123—0 upon 20 the lamps of the indicator, if, as assumed, the indicator mechanism has functioned accurately.

The sequence switch of the testing device, 25 upon leaving position 17 $\frac{1}{4}$, continues in its rotation, and upon passing through positions 18 to 18 $\frac{1}{4}$, inclusive, closes a circuit for the cut-off relay 418, which circuit may be traced from battery, through the winding of relay 418, the left contacts of cam 417 (18 to 18 $\frac{1}{4}$) to ground. Relay 418, upon energizing, locks over its left armature and front contact, conductor 419, to ground through the left normal contacts of keys 308 and 309, and closes a circuit from ground on conductor 419, through its outer right armature and front contact, through the back contact of relay 439, and supervisory relay 438, to battery, and opens the circuit of release magnet 400 of the sequence switch at the back 30 contact of its left armature so that the release magnet cannot again be operated when the sequence switch reaches its normal position until after the disconnect key 308 has been depressed. The lighting of the supervisory lamp 438 at this time indicates that 35 the test number has been recorded upon the lamps of the indicator mechanism. When the sequence switch reaches position 1 with magnet 400 deenergized, the detent on the armature of magnet 400 engages a notch in the disc 480 on the shaft of the sequence switch arresting the sequence switch.

At the indicator under test upon the energization of relay 533 during the transmission of the tens code of impulses, a circuit was established from ground at the inner left armature of relay 533, thence by parallel paths through the winding of relay 539, to battery, and through the left armature 40 and back contact of relay 540 and the winding of slow to release relay 541, to battery. Relay 539, upon energizing, closed a circuit for the No. 0 thousands lamp 617, which may be traced from battery, the right armature and front contact of relay 539, conduc-

tor 542, the inner right armature and back contact of relay 603, the inner left armature and back contact of relay 601, the outer right armature and back contact of relay 600, the left armature and back contact of relay 602, lamp 617, the outer right armature and back contact of relay 601, the outer left armature and back contact of relay 600, the outer right armature and back contact of relay 602, conductor 616, to ground at the 75 left armature of relay 539. A circuit for the No. 1 hundreds lamp 618 was also established by relay 539 as follows: battery, right armature and front contact of relay 539, conductor 543, the inner right armature and back contact of relay 607, inner left armature and back contact of relay 605, the outer right armature and front contact of relay 604, lamp 618, normal contacts of 80 the outer left armature of relay 605, the outer left armature and back contact of relay 607, conductor 619, to ground at the left armature and front contact of relay 539.

During the transmission of the units code impulses, relay 537 energized as previously described, and at its outer right hand armature closed a circuit for relay 540, which may be traced from battery through the winding of relay 540, outer right armature and contact of relay 537, to ground at the inner left armature and contact of relay 533. Relay 540, upon energizing, opened the circuit of relay 541, which being slow to release, after a predetermined interval which is designed to give sufficient time for the transmission of a final strong positive impulse where such an impulse is required, closed a circuit which may be traced from ground at its armature and back contact, through the right armature and contact of relay 540, conductor 544, the winding of relay 507, conductor 545 to battery through the winding of relay 546. Relays 507 and 546 both energized, relay 546 closing a locking circuit for itself and for relay 507 which may be traced from battery, through the windings of relays 546 and 507, the inner left armature and contact of relay 546, conductor 547, the outer right armature and contact of relay 537, to ground at the inner left armature and contact of relay 533. A circuit is now established for the No. 2 tens lamp 620, which may be traced from battery, through the inner left armature and front contact of relay 537, conductor 548, the inner right armature and back contact of relay 611, the inner left armature and front contact of relay 609, inner left armature and back contact of relay 608, lamp 620, inner right armature and front contact of relay 609, outer 105 left armature and contact of relay 608, outer right armature and back contact of relay 610, conductor 621, the outer right armature and contact of relay 537, to ground at the inner left armature and contact of relay 533. 110

A circuit is also established for the No. 3 units lamp 622 as follows; battery, right armature and contact of relay 546, conductor 549, the inner right armature and back contact of relay 615, the inner left armature and front contact of relay 613, the inner left armature and front contact of relay 612, lamp 622 the outer left armature and front contact of relay 613, the outer left armature and back contact of relay 615, conductor 623, to ground at the outer left armature and contact of relay 546. A circuit is also established upon the energization of relay 546 for relay 550, which extends from battery, through the winding of relay 550, to ground at the outer left armature and contact of relay 546. This relay prepares circuits for the stations lamps, but since, as previously stated, the stations designation was 0, none of the stations lamp relays 521 to 525, inclusive, were operated. Therefore, no circuits for the stations lamps are completed at this time by relay 550. The entire designation of the test number 0123-6 is now displayed upon the lamps of the indicator.

The energization of relay 507 upon the completion of the code impulses, opens at the back contact of its right armature the circuit previously traced through the winding of relay 505 of the indicator control circuit and the winding of relay 411 of the testing device, allowing these relays to release. The number, however, will remain displayed on the indicator until the disconnect key 308 of the testing device is depressed. The test man, upon observing the number displayed on the indicator lamps, checks it against the number set up on the keyboard of the testing device, and if found to be accurate, proceeds to wipe out the displayed number by depressing disconnect key 308, which is instrumental in opening the holding circuit previously traced through the windings of relay 403 and the winding of holding relay 502 of the indicator. Relay 502, upon deenergizing, disconnects ground from the holding conductors 508 and 509, thereby causing the deenergization of all operated relays of the indicator and the extinguishing of all the lighted lamps. At the testing device relay 403 deenergizes and relay 418, which was held energized through the left normal contact of key 308, also deenergizes. The circuits of the testing device are now in condition for the initiation of the next test, which is now made with the second test number indicated in the foregoing table.

To initiate this test, the test man depresses the No. 1 thousands key 333, the No. 2 hundreds key 334, the No. 3 tens key, 335, the No. 4 units key 336 and the R stations key 337, winds the spring of the sequence switch, and depresses the starting key 300.

From this point the test proceeds in the manner previously described in connection with the first test number, and if the indicator functions accurately, the test number 1234-R becomes displayed on the lamps of the indicator. The test man upon noting the correct display of the second test number, depresses the disconnect key 309, which causes operation at the indicator simulating those which take place as a result of the depressing of an assignment key, such as 211, of a trunk other than the one to which the display number belongs. The depression of key 309 bridges a resistance of 60 ohms around the winding of relay 403 in a circuit which may be traced from the left terminal of relay 403, conductor 310, the right normal contact of key 308, resistance 329, the right contact of key 309, conductor 311, spring 407 of key 402 and its normal contact, conductor 408, ring of jack 103, ring strand of cord 108, ring of jack 111, conductor 119, the armature and contact of relay 505, winding of relay 551, contact of relay 504, to ground at the right armature and front contact of relay 507. It is to be noted that relay 507 is energized at this time since the test number has been completely recorded on the lamp relays of the indicator. Relay 551, being of low resistance, the energization of relay 403 cannot continue and relay 403 thereupon releases, permitting relay 551 to energize in series with relay 502, which relay was energized at the initiation of the test. The circuit over which relay 551 is now energized is as follows: battery, winding of relay 502, conductor 503, sleeve of jack 111, sleeve strand of cord 108, sleeve of jack 103, conductor 118, spring 404 of key 402, and its normal contact, conductor 405, resistance 329, contact of key 309, thence as previously traced through the winding of relay 551, to ground at the right armature and front contact of relay 507. Relay 551, upon energizing, closes an obvious circuit for relay 510, which at its inner left armature and contact locks to ground at the right armature and front contact of relay 507, and at its outer left armature and back contact and right armature and back contact removes ground from the holding conductors 508 and 509, respectively, thus causing the release of all operated relays of the indicator and the wiping out of the displayed number. If no trouble occurs on the second test number, the next test call, as shown in the foregoing table, is transmitted, until all ten of the test calls have been completed, the succeeding test calls being released through the alternate employment of disconnect keys 308 and 309.

The test man thereupon depresses group key 328, thereby restoring group key 302, and repeats the ten test calls for the purpose of testing the indicator over an im-

pulse circuit which has a lower resistance and higher potential, simulating the other extreme condition under which the indicator must function in actual service. The 5 operation of key 328 causes the inclusion of resistance elements 312 to 316, inclusive in the impulse circuits extending through cams of the sequence switch and through the windings of relays 500, 513 and 514, these 10 resistances having a total resistance of 2000 ohms, and the substitution of a 52 volt operating battery for the 45 volt battery 126 employed in the previous tests. The transfer from battery 126 to the 52 volt battery 15 127, is brought about through the operation of relay 125 over a circuit extending from battery, through the winding of this relay, the sleeve of jack 114, the sleeve of cord 108, sleeve of jack 101, conductor 128, the 20 right contact of key 328, to ground.

If the indicator control circuit is provided with a second marginal relay for permitting the control circuit to be employed with trunk circuits having a wider range of loop 25 resistance, the tests above described are again repeated with the key 401 depressed and the appropriate group keys depressed. If it be assumed that the marginal relay 501 of the indicator test is adjusted for operation 30 over a range of from 800 to 1700 ohms loop resistance, then the ten test calls in accordance with the foregoing table, are first established with the key 330 depressed, and again established with the key 331 depressed. The operation of key 401 transfers 35 conductor 423 of the impulse circuit from conductor 123, which as hereinbefore described is connected through the winding of marginal relay 500, thence through the 40 windings of relays 513 and 514, to conductor 129, which is connected over the sleeve of jack 104, sleeve of cord 109, sleeve of jack 112, conductor 130, through the winding of the second marginal relay 501, and thence 45 through the windings of relays 514 and 513. The marginal relay 501 functions in conjunction with relays 513 and 514 in exactly the same manner as previously described in connection with test calls employing marginal relay 500.

If the indicator mechanism fails to correctly indicate the number of any test call, this failure may be due to improper adjustment of either marginal relay 500 or 501, or 55 sensitive polarized relays 513 or 514, failure of the transfer relays, or failure of the lamp relays to operate or to lock up after operation. If incorrect numbers are displayed, certain digits of which are correct with one 60 or more of them wrong, the trouble may be due to the failure of the negatively polarized relay 514 to function properly, the inaccurate adjustment of relays 517 or 518, or failure of the transfer relays 519, 520, 526, 65 527, 528, 529, 533, 534, 537 or 511 to operate.

A comparison of the numbers set up on the keyboard by the test man and the numbers actually displayed by the indicator under test, enables the test man to analyze the source of the trouble if any occurs, and if 70 faulty relay adjustments are indicated the relays may then be adjusted in the regular manner by means of a relay adjusting test set.

The sensitive polarized relays 513 and 75 514, may if desired, be tested from the testing device. To test either of these relays key 320 is depressed to remove the shunt from around the resistance element 332 having a total resistance of 21,700 ohms, and 80 keys 416 and 300 are then depressed in succession. The operation of key 416 prior to the operation of start key 300 opens the circuit of release magnet 400 at the normal contact of key 416 so that when the test is 85 started through the operation of key 300, the sequence switch is not released at the time relay 411 energizes.

If the negatively polarized relay 514, for example, is to be tested, key 442 is depressed 90 ten times, or a sufficient number of times to operate all of the transfer relays of the indicator. Upon each depression of the key, a circuit is established for relay 514 which may be traced from the non-grounded pole of battery 126, the armature and back contact of relay 125, the left armature and front contact of relay 124, ring of jack 115, ring strand of cord 107, ring of jack 102, conductor 427, resistance 429, resistance 428, the right contact of key 442, the left normal contact of key 440, right armature and front contact of relay 411, conductor 321, resistance 332, conductor 319, group key 302, resistances 312 to 318, inclusive, conductor 423, normal contact of key 401, conductor 123, ring of jack 104, ring strand of cord 109, ring of jack 112, conductor 516, thence as previously traced through the windings 100 of relays 500, 513 and 514, returning over conductor 122, tip of jack 112, tip strand of cord 109, tip of jack 104, conductor 422, left armature and back contact of relay 413, conductor 421, outer left armature and front contact of relay 411, right normal contact 105 of key 440, left contact of key 442, conductor 121, to ground at jack 114. Polarized relay 514 should not operate over a circuit including resistance 332, and no lamps of the indicator should light.

If lamps of the indicator light the test man then knows that the relay 514 needs adjustment. 110 If it is desired to test the positively polarized relay 513, the number 2000-0 is transmitted by employing the step-by-step keys 440, 441 and 442. For transmitting the thousands digit 2, a positive and two negative impulses are transmitted, and for each of the remaining digits of the number two negative impulses are sent. Thus, for the 115

120 125 130

entire number, one positive and ten negative impulses are required. For the transmission of the first positive impulse the key 320 is maintained operated and the key 440 5 is depressed once, the impulse circuit extending as previously traced for testing relay 514, but with the terminals of battery 126 connected reversely therein. Following the transmission of the single positive 10 pulse, the key 320 is opened to remove resistance 332 from the circuit, and key 442 is then operated ten times. If the number 2000-0 appears on the indicator, it is an 15 indication that the positively polarized relay 513 has operated over a loop containing the high resistance 332 when it should not have operated, and that it is therefore out of adjustment.

It may also be desirable to transmit 20 pulses of a test number more slowly than can be done through the use of the sequence switch in order that the test man may more closely observe the operation of the indicator under test. This may readily be accomplished through the operation of keys 25 440, 441 and 442, which for that reason may be known as the step-by-step keys. To operate an indicator step-by-step the key 416 is first operated to prevent the release of the 30 sequence switch when the start key 300 is depressed. The start key 300 is then depressed, operating relays 403 and 411 as previously described. When key 416 is in its alternate position, a circuit is established 35 for the lamp 443, which may be traced from battery, through the lamp 443, alternate contact of key 416, the inner left armature and front contact of relay 411, the right contacts of cam 417 (1), the left 40 armature and back contact of relay 418, conductor 419, and to ground at key 309. The illumination of lamp 443 signals the test man that he may proceed to transmit impulses through the operation of keys 440, 45 441 and 442. To send a negative impulse for operating the negatively polarized relay 514, key 442 is operated. To send a positive impulse for operating the positively polarized relay 513, key 440 is operated, and 50 to send a strong impulse of either positive or negative polarity, the key 441 is operated in conjunction with either key 440 or key 442. It is to be noted that when key 441 is depressed, the high resistance 428 is 55 short-circuited at the right contact of this key and the right contact of either key 440 or 442, so that the current flowing through the contacts of either key 440 or 442 and the windings of relays 500, 513 and 514 is 60 strong enough to energize the marginal relay 500 in addition to either relay 513 or 514.

To test the indicator control circuit with 65 respect to the accuracy with which it functions in controlling ringing current selec-

tion, the test man successively sets up test call numbers 0000-J, 0000-R, 0000-M and 0000-W upon the keyboard, and conducts a regular test of the control circuit for each of these numbers in the manner 70 previously described. For the test number 0000-J, only stations relay 524 should be operated. With only relay 524 operated, no ground connections are made with conductors 552 and 553, and therefore no circuits are effective for relays 465 and 466 of the test device. With both relays 465 and 466 deenergized, none of the lamps 467, 468 or 469 is illuminated and the test man is apprised of the fact that ringing selection 80 for the party J has been correctly performed.

For the second ringing test call, 0000-R, stations relays 521, 522 and 523 are energized, and a circuit is established for relay 85 465 which may be traced from battery, through the winding of relay 465, the normal contact of key 456, the right normal contact of key 457, conductor 142, tip of jack 100, tip strand of cord 105, tip of jack 110, conductor 161, conductor 552, the left armature and front contact of relay 522, to ground at the outer right armature and front contact of relay 523. Relay 465, upon energizing, establishes a circuit for 90 lamp 468, which may be traced from battery, through lamp 468, right armature and front contact of relay 465, to ground at the left armature and back contact of relay 466. If lamp 468 lights, as it should, it 100 indicates to the test man that ringing selection for the party R has been accurately performed.

For the third ringing test call in accordance with the designation 0000-M, stations 105 lamp relay 525 only is operated, and a circuit should therefore be effective for relay 466, which may be traced from battery, through the winding of relay 466, the right normal contact of key 458, the left normal contact of key 457, conductor 146, ring of jack 100, ring strand of cord 105, ring of jack 110, conductor 162, conductor 553, to ground through the outer right armature and contact of relay 525. If relay 466 110 operates, a circuit is established for lamp 469, which may be traced from battery, through the lamp 469, the left armature and front contact of relay 446, to ground at the right armature and back contact of relay 465, indicating to the test man that ringing selection for the party M has been 115 successfully performed.

On the fourth ringing test call for the party W ringing selection, stations relay 120 523 only is operated, and circuits are thereupon established for both relays 465 and 466, the circuit of relay 465 extending, as previously traced, over conductor 552, the left armature and back contact of relay 125 553.

522, to ground at the outer right armature and contact of relay 523, and the circuit of relay 466 extending as previously traced, over conductor 553, the right armature and back contact of relay 522, the inner left armature and front contact of relay 523, the inner left armatures and back contacts of relays 524 and 525, to ground at the inner left armature and contact of relay 528. With both relays 465 and 466 energized, a circuit is established for lamp 467, which may be traced from battery, through lamp 467, the right armature and contact of relay 466, and to ground at the left armature and contact of relay 465. If the lamp 467 is lighted, as it should be, it is an indication to the test man that the control circuit has functioned properly for selecting ringing current for 20 ringing the party W on a party line.

Upon the completion of the test of the indicator, the patching cords 105 to 109 are removed from the jacks 110 to 115, inclusive, releasing the testing device from the indicator, and if the indicator is found to function accurately, or after adjustment is caused to function accurately, the cord circuits of the operator's position are disconnected from the emergency indicator apparatus and connected to the indicator which has just been tested.

Testing a trunk circuit.

Before proceeding to test a trunk circuit the trunk is first made busy at its outgoing end so that it may not be taken for use at the machine switching office to which it extends during the test, and the cord circuits 35 105 to 109, inclusive, are plugged into the jacks 100 to 104, inclusive, of the testing device and into jacks 113 to 117, respectively. It will now be noted that by the connection of cord 109 to jacks 104 and 117, the testing device is connected to the tip and ring 40 strands 206 and 207 of the incoming end of the trunk circuit to be tested. The test man now throws the trunk testing key 402 to its alternate position, operates the proper group key for applying 45 volt battery and the 45 higher loop resistance over which the operator's indicator is designed to operate, in 50 this instance key 302, sets up the test number 00000 on the keyboard, winds the spring of the sequence switch, and depresses start key 55 300. The designation 00000 is the official designation of the test line terminating before the operator's position in jack 227, and is recognized as a test call when this designation appears upon the lamps of the operator's call indicator.

Upon the operation of key 300 a circuit is established for relay 413, which may be traced from battery, through the right winding of relay 413, conductor 444, left contact 60 of key 300, conductor 445, alternate contact

of spring 446 of key 402, inner right armature and back contact of relay 403, conductor 410, spring 409 of key 402 and its alternate contact, conductor 447, outer right armature and back contact of relay 418, conductor 419, to ground at the normal contact of key 309. Upon the release of key 300, relay 413 locks through its inner right armature and front contact, through the spring 446 and its alternate contact of key 402, to ground at the 75 contact of key 309, and at its left armature and front contact closes a circuit extending from the testing device over the strands 206 and 207 of the trunk under test, through the windings of trunk relay 200. This circuit 80 may be traced from ground, through the left winding of relay 200, the left normal contact of relay 201, the lower left winding of repeating coil 202, the innermost lower armatures and back contacts of relays 204 and 205, conductor 206, ring of jack 117, ring strand of cord 109, ring of jack 104, conductor 123, normal contact of key 401, conductor 423, resistances 312 to 318, inclusive, 85 left contact of key 302, conductor 319, normal contact of key 320, conductors 321 and 448, contacts of key 449, winding of relay 451, the left armature and contact of relay 413, conductor 422, tip of jack 104, tip strand of cord 109, tip of jack 117, conductor 207, 90 innermost upper armatures and back contacts of relays 205 and 204, conductor 208, upper left winding of repeating coil 202, right normal contacts of relay 201, to battery through the right winding of relay 200. Relays 200 and 451 both energize in this circuit, relay 451 closing a circuit extending from ground, through the left winding of relay 413, the armature and contact of relay 451, the left winding of relay 403, to battery at the alternate contact of spring 452 of key 402. Relay 403, upon operating, locks over a circuit extending from battery at spring 452, through both of its windings, its inner right armature and front contact, the alternate contact of spring 409 of key 402, conductor 447, the outer right armature and back contact of relay 418, conductor 419, to ground at the left normal contact of key 309, and its inner right armature and back contact opens the locking circuit of relay 413. Relay 413, however, is maintained energized in series with the left winding of relay 403.

At the trunk circuit under test relay 200, upon energizing, closes a circuit for relay 209, which may be traced from battery at the outer right armature and back contact of relay 210, winding of relay 209, the right armature and back contact of relay 212, to ground at the armature and contact of relay 200. Relay 209, upon energizing, closes a locking circuit for itself extending from battery, through its outer right armature and contact, its winding, and to ground at the 120 125 130

5 armature and contact of relay 200, and at its inner right armature and front contact establishes a circuit for the assignment lamp 213. This circuit may be traced from bat-
 10 tery, through lamp 213, the left non-inductive winding of relay 214, the inner right armature and front contact of relay 209, to ground. The operator, noting the illumination of lamp 213, depresses the assignment
 15 key 211 associated with the trunk circuit corresponding to the lighted lamp 213, whereupon a circuit is established for the assignment relay 215. This circuit may be traced from battery, through the winding of
 20 relay 502, conductor 503, conductor 216, the lower armature and back contact of relay 217, conductor 218, the right winding of relay 215, the outer left armature and front contact of relay 209, the upper contact of
 25 key 211, conductor 119, the armature and contact of relay 505, conductor 506, to ground at the left armature and back contact of relay 507. Relays 502 and 215 energize in this circuit, relay 502 connecting ground to
 30 the holding conductors 508 and 509 in the manner previously described to prepare the indicator circuits for operation.

35 Relay 215, upon energizing, closes a locking circuit for itself extending from bat-
 30 tery on conductor 218, through both of its windings, to ground at the front contact of its inner left armature. Relay 215 also closes an obvious circuit for relay 210, which in turn opens the initial energizing circuit
 35 of relay 209 and closes a circuit for relay 214, which may be traced from ground, through the right winding of relay 214, the inner right armature and front contact of relay 210, to battery at the outer right arm-
 40 ture and contact of relay 209. Relay 210 also prepares a flashing circuit for the lamp 213, which later becomes effective following the deenergization of relay 209. With relays 214 and 215 now energized, a circuit
 45 is closed for relay 205 which may be traced from battery, through the left armature and contact of relay 214, conductor 219, winding of relay 205, conductor 220, outer left armature and contact of relay 215, con-
 50 ductor 120, winding of relay 505, to ground at the right armature and back contact of relay 507. Relays 205 and 505 energize in this circuit, relay 205 disconnecting the windings of relay 200 from the trunk con-
 55 ductors 207 and 206, and extending these conductors over conductors 122 and 516, res-
 60 pectively, to the windings of relays 500, 513 and 514 in the manner previously de-
 scribed.

65 Upon the disconnection of relay 200 following the energization of relay 205, the locking circuit of relay 209 is opened and relay 209 deenergizes, opening the previously traced circuit of lamp 213 and connecting this lamp in a circuit extending from bat-

70 tery, through the left winding of relay 214, the inner right armature and back contact of relay 209, left armature and front contact of relay 210, the lower armature and back contact of relay 221, to ground through in-
 75 terrupter 222 for flashing the lamp 213 until the operator extends the connection by plugging up plug 223 after the line designation has been displayed on the lamps of the call indicator. Upon the deenergization of re-
 80 lay 209, the initial energizing circuit of relay 214 is opened at the outer right armature and contact of relay 209, relay 214 being now maintained energized in a holding circuit extending through its winding, its inner right armature and front contact, to battery through the winding of relay 212. Relay 212, upon energizing in this holding circuit, opens the initial energizing circuit of relay 209 and prepares a locking circuit for itself which is effective upon the reenergization of relay 200, as will hereinafter appear.

85 At the testing device, upon the disconnection of relay 200 through the operation of relay 205, relay 451 deenergizes, opening the holding circuit of relay 413 which in turn deenergizes and closes a circuit for relay 411. This latter circuit may be traced from battery, through the winding of relay 411, conductor 412, the left armature and contact of relay 403, the outer right armature and back contact of relay 413, to ground at the uppermost alternate contact of key 402. Relay 411, upon energizing, closes the previously traced circuit for the sequence switch release magnet 400 to start the sequence switch, and connects the cams of the sequence switch over conductors 423 and 421 to the previously traced circuit extending through the windings of relays 500, 513 and 514 of the operator's call indicator. The sequence switch thereupon functions to transmit a series of light negative impulses for setting up the designation 00000 upon the lamp relays of the indicator, it being recalled that this designation was recorded by the test man upon the keyboard of the test device.

90 As soon as the sequence switch reaches position 18 following the transmission of all of the code impulses, the circuit of relay 418 is established as previously described, this relay locking through its left armature and front contact, to ground at the normal contact of key 309. Relay 418 also 95 opens the locking circuit of relay 403, which thereupon deenergizes, opening the circuit of relay 411. Relay 418 also closes a circuit through the supervisory lamp 438, as previously described, to indicate that the code impulses have all been transmitted. Relay 418 also connects the windings of relays 439 and 453 to the back contacts of relay 411 for a purpose which will later appear.

At the call indicator, as soon as the last impulses have been received, the number 00000 becomes displayed upon the indicator lamps, and relays 507 and 546 become energized in the manner previously described. Relay 507, upon energizing opens the circuit of relays 505 and 205 thereby causing the release of these relays. Relay 205, upon deenergizing disconnects conductors 122 and 516 from the trunk conductors 207 and 206, and reconnects the trunk conductors with the windings of relay 200. Relay 200 now becomes energized in series with the windings of relays 439 and 453 over the following circuit: ground, left winding of relay 200, left normal contacts of relay 201, lower left winding of repeating coil 202, conductor 203, the innermost lower armatures and back contacts of relays 204 and 205, conductor 206, ring of jack 117, ring strand of cord 109, ring of jack 104, conductor 123; normal contact of key 401, conductor 423, resistances 312 to 318, inclusive, left contact of key 302, conductor 319, normal contact of key 320, conductors 321 and 424, right armature and back contact of relay 411, inner right armature and front contact of relay 418, right winding of relay 453, winding of polarized relay 439, left winding of relay 453, outer left armature and back contact of relay 411, conductor 421, left armature and back contact of relay 413, conductor 422, tip of jack 104, tip strand of cord 109, tip of jack 117, conductor 207, innermost upper armatures and back contacts of relays 205 and 204, upper left winding of relay 202, right normal contacts of relay 201, right winding of relay 200, to battery. With relay 200, energized, a locking circuit is established for relay 212 in shunt of the right winding of relay 214, thereby causing the deenergization of relay 214. Relay 214 thiereupon deenergizes, opening at its left armature and front contact the initial energizing circuit of relay 205. At the testing device relay 453 energizes, establishing an obvious circuit for the lamp 454, indicating to the test man that the trunk has been closed through from the testing device to the operator's trunk circuit. Relay 439 being polarized, is not energized at this time.

The operator, noting the illumination of the lamps of the indicator, picks up the plug 223 of the trunk circuit designated by the flashing lamp 213, and tests the sleeve of jack 227, and then inserts the plug in the jack. Upon the insertion of the plug in the jack, sleeve relay 217 is energized in a circuit which may be traced from battery, through the winding of relay 228, right armature and back contact of relay 229, armature and back contact of relay 230, outer left armature and contact of relay 212, outer right armature and back contact of relay 214, winding of relay 217, sleeve of plug

223, sleeve of jack 227, conductor 225, to ground through the winding of relay 130. Lamp 224 being shunted by the winding of relay 228 does not energize at this time in series with relays 217 and 130. Relays 217 and 130 energize in this circuit, relay 217 disconnecting the tip of the plug 223 from conductor 226, which extends through the upper armature and contact of relay 221 to the test winding of the operator's head set, and connects the tip of the plug to the tip strand 227 of the trunk circuit. Relay 217 at its lower armature and back contact opens the holding circuit previously traced through the windings of relays 215 and 502, whereupon these relays deenergize, relay 502 disconnecting ground potential from the holding conductors 508 and 509, thus releasing all energized relays of the call indicator and extinguishing the lighted lamps. Relay 215, upon deenergizing, opens the circuit of relay 210, whereupon the circuit over which lamp 213 was flashed is opened.

Relay 130, upon energizing, now closes a circuit extending from ground at its armature contact, over conductor 131, sleeve of jack 113, sleeve strand of cord 105, sleeve of jack 100, through lamp 455, to battery, and lamp 455 operates to indicate to the test man that the operator has plugged up the cord of her trunk circuit in the jack 227 of the test line.

Ringing relay 228, upon energizing, closes a circuit for connecting a source of ringing current to the conductors of the test line. Since neither of the ringing selection relays 232 or 233 has been operated, the circuit over which ringing current is applied may be traced from the source of ringing current 231, through the left hand winding of marginal ringing cut-off relay 230, upper armature and back contact of relay 232, the innermost upper armature and back contact of relay 233, the lower armature and front contact of ringing relay 228; ring of plug 223, ring of jack 227, conductor 234, left armature and back contact of relay 132, conductor 133, the windings of relays 134 to 137, inclusive, in parallel, conductor 138, the right armature and back contact of relay 132, conductor 235, tip of jack 227, tip of plug 223, upper armature and front contact of relay 217, upper armature and front contact of relay 228, to ground at the innermost lower armature and back contact of relay 233. Relays 134 to 137, inclusive, energize in this circuit, but relay 230 being marginal, does not receive sufficient current to cause its energization. Since both relays 232 and 233 are deenergized, current from the source 231 is applied to the ring conductor 234 of the test line in such a manner as to cause only the operation of biased ringer 139, current from the source 231 flowing over the ring conductor 234 as previously traced through

conductor 133, ringer 139, and to ground at the armature contact of relay 134.

In response to the ringing of ringer 139, the test man depresses and then immediately releases key 456. Upon the depression of key 456, a circuit is closed from battery, through the winding of trip relay 140, conductor 141, tip of jack 113, tip strand of cord 105, tip of jack 100, conductor 142, normal right contact of key 457, alternate contact of key 456 to ground. Relay 140, upon energizing, shunts the high resistance 143 and connects the low resistance 144 directly across conductors 133 and 138. The current now flowing from the source 231 over the test line through the armature contact of relay 140 and the low resistance 144, is sufficient to cause the energization of marginal relay 230, which upon energizing, opens the shunt around the winding of relay 229. Relay 229 now energizes in series with relay 228, sleeve relay 217 and relay 130 in the circuit previously traced, and at its right armature and front contact closes a locking circuit for itself and for relays 217 and 130, and shunts the winding of ringing relay 228. Relay 228 now deenergizes, disconnecting the source of ringing current 231 from the conductors of the test line, whereupon relays 134 to 137, inclusive, deenergize, relay 134 disconnecting the ringer 139 from the ring conductor 133.

A circuit is now established for the supervisory relay 236 of the trunk circuit, which may be traced from the non-grounded pole of battery, the lower right winding of repeating coil 202, winding of relay 236, the lower armature and back contact of relay 228, ring of plug 223, ring of jack 227, conductor 234, left armature and back contact of relay 132, resistances 143 and 144, relay 140 having released upon the release of key 456, right armature and back contact of relay 132, conductor 235, tip of jack 227, tip of plug 223, upper armature and front contact of relay 217, upper armature and back contact of relay 228, to ground through the upper right winding of repeating coil 202. Relay 236, upon energizing, closes a circuit for reversing relay 201, which may be traced from battery, through relay 201, the armature and contact of relay 236, to ground at the left armature and contact of relay 229. Relay 201, upon energizing, reverses the connections between the windings of trunk relay 200 and the strands 206 and 207 of the trunk circuit, whereupon the polarized relay 439 of the testing device receives current in the proper direction to cause its operation. The circuit of supervisory lamp 438 is now opened, indicating to the test man that ringing current has been tripped properly and that the supervisory relay of the trunk circuit has op-

erated as it would in actual service upon 65 the response of a called subscriber.

The test man may now conduct tests to determine if the various relays of the trunk circuit are functioning properly. To test the trunk supervisory relay 236, the test 70 key 458 is operated and locked in its operated position, and switch 450 is wound up and permitted to make a single revolution. During the revolution of switch 450, the matching lamp 443 and the supervisory lamp 438 are operated in unison, both lamps being extinguished for three seconds, lighted for the next one-half second, and extinguished for the next one-half second and 75 then again lighted. In detail, the operation of key 458 closes the following circuit for relay 132: from battery, through the winding of relay 132, conductor 145, ring of jack 113, ring strand of cord 105, ring of jack 100, conductor 146, the left 80 normal contact of key 457, to ground at the right alternate contact of key 458. Relay 132, upon operating, disconnects conductors 133 and 138 from the test line conductors 234 and 235, and connects a high 85 resistance bridge across the test line conductors, which may be traced from conductor 234, the left armature and front contact of relay 132, conductor 147, resistance 148, rheostat 149, ammeter 153, rheostat 150, resistances 154 and 151, conductor 152, right armature and front contact of relay 132, to conductor 235. Key 458 at its left alternate contact also closes an obvious circuit 90 for the matching lamp 443.

As the switch 450 starts rotating, contact 460 closes and contact 461 opens. The opening of contact 461 opens the circuit of lamp 443 and the closure of contact 460 connects a shunt around resistance 148, rheostats 149 and 150, and resistance 154, leaving only the resistance 151 of ten ohms in the circuit of supervisory relay 236. This shunt circuit may be traced from conductor 147, conductor 155, sleeve of jack 116, sleeve 100 strand of cord 108, sleeve of jack 103, conductor 118, alternate contact of spring 404 of key 402, conductor 462, contact 460, alternate contact of spring 414 of key 402, conductor 415, tip of jack 103, tip strand of 105 cord 108, tip of jack 116, conductor 156, to the junction point between resistances 154 and 151. The current now flowing through the winding of supervisory relay 236 is sufficient to thoroughly saturate its 110 magnet circuit or "soak" the relay. After three seconds the contact 460 opens, and the shunt is thereby removed from about resistances 148 and 154 and rheostats 149 and 150 for a period of one-half a second, and relay 236 is again included in circuit 115 with the entire resistance. Under these conditions relay 236 should release, releasing 120 125

relay 201 and causing the reversal of current through the winding of polarized supervisory relay 439 of the testing device. Upon the reversal of current through the 5 winding of relay 439, this relay releases, again closing the circuit of lamp 438, and since at this time contacts 461 are closed, lamp 443 is again lighted. With both lamps lighted, the test man is apprised of 10 the fact that relay 236 has released, as it should.

During the continued rotation of switch 450, the cams thereof for the next one-half second close contact 459 and open contact 15 461, the contact 460 remaining open. With contact 459 closed, a shunt is established about resistance 148 and rheostat 149, thereby reducing the resistance in circuit with relay 236 to 1100 ohms. This shunt may be 20 traced from conductor 147, over conductor 155, sleeve of jack 116, sleeve strand of cord 108, sleeve of jack 103, conductor 118, spring 404 of key 402 and its alternate contact, conductor 462, contact 459, alternate contact of 25 spring 407 of key 402, conductor 408, ring of jack 103, ring strand of cord 108, ring of jack 116, conductor 157, to a point between rheostats 149 and 150. Supervisory relay 236 should now operate, causing a further 30 reversal of current through the winding of polarized relay 439, thereby causing the energization of relay 439. If relay 439 energizes, the lamp 438 is again extinguished, while the matching lamp 443 is extinguished, 35 by the opening of contact 461, and thus the test man is apprised of the fact that the supervisory relay 236 has energized properly and is therefore adjusted for operation between the proper operating and non-operating limits. During the remainder of 40 the revolution of switch 450, both contacts 459 and 460 are opened, again connecting the entire resistance in the circuit of relay 236.

45 A further test of supervisory relay 236 may be made with the test key 458 depressed by operating key 463 at the rate of three times per second for the purpose of ascertaining if the supervisory relay 236 will 50 respond to the rapid opening and closing of its circuit, simulating the movement of a called subscriber's switchhook for flashing or recalling the operator. The key 463 accomplishes the same results as the successive 55 closures of spring 459 through the revolution of switch 450, and for each depression and release thereof should operate and extinguish the supervisory lamp 438.

60 If the supervisory relay does not operate properly on these tests, the test man may then restore the test key 458 and depress the locking adjusting key 457 for the purpose of making adjustment tests of the supervisory relay. Upon the operation of key 65 457, a circuit is closed extending from

ground at its left alternate contact, over conductor 146, ring of jack 100, ring strand of cord 105, ring of jack 113, conductor 145, through the winding of relay 132, to battery. Relay 132, upon energizing, connects 70 resistances 148, 151 and 154 and rheostats 149 and 150 to conductors 234 and 235 of the test line and thus in series with supervisory relay 236 in the manner previously described. The test man may then adjust the rheostats 75 until the proper releasing resistance is included in the circuit of relay 236, which in this case may be assumed to be 4,347 ohms. The supervisory relay 236 is then adjusted so that it will respond when the key 463 is 80 depressed, reducing the resistance in circuit of relay 236 to 1,317 ohms after its winding has been soaked for three seconds by the depression of key 470, which functions the same as contacts 460 to reduce the resistance 85 in circuit with relay 236 to 10 ohms.

Testing trunk circuit for selectively ringing substations on four party lines.

The accuracy with which the relays function to apply ringing current for ringing the party J on a line may be tested by operating the key 402, a group key, for example, 302, winding the sequence switch of the testing device and setting up the number 0000—J upon the keyboard of the testing device. The test man then depresses start key 300, whereupon code impulses are transmitted which are instrumental in operating only the stations lamp relay 524. Following the transmission of the code impulses, the number 0000—J becomes displayed upon the lamp of the indicator, but neither of the selection relays 232 or 233 of the trunk circuit are operated. The operator recognizes this number as a test line call and connects the trunk circuit under test with the test line 234, 235, whereupon relays 130, 217 and 228 operate in series, as previously described, and ringing current is applied, as 110 hereinbefore described, for operating the ringer 139, which corresponds to the party J of a party line.

If the bell 139 rings, as it should, the test man depresses the disconnect key 308, 115 causing the display of the disconnect signal 224 of the trunk circuit in the following manner. When the key 308 is depressed, the locking circuit of relay 418 is opened, thereby opening the loop circuit extending 120 through the windings of relays 439 and 453 of the testing device and the trunk relay 200. Relay 200, upon deenergizing, opens the locking circuit of relay 212, which in turn opens the circuit extending from battery, through the right armature and front contact of relay 229, the winding of relay 229, outer left armature and contact of relay 212, the outer right armature and back contact of relay 214, the winding of relay 130

217, sleeve of plug 223, sleeve of jack 227, conductor 225, to ground through the winding of relay 130. The opening of this circuit removes the shunt from around the 5 connect lamp 224, whereupon this lamp lights in series with relays 217 and 130. The operator, noting the illumination of disconnect lamp 224, removes the plug 223 from the jack 227, whereupon the apparatus of 10 the trunk circuit is restored to normal condition. The apparatus of the testing device and of the trunk circuit is now in condition for another test call.

To test the trunk circuit for ringing the 15 party R, the test man repeats the same operation as for the previous test except that in this case he sets up the designation 0000—R on the keyboard. The circuits of the trunk and indicator now function as previously 20 described except that stations relays 521, 522 and 523 are operated and the designation 0000—R becomes displayed. With relays 522 and 523 energized, a circuit is closed from ground at the outer right contact 25 of relay 523, left armature and front contact of relay 522, conductor 552, the upper armature and front contact of relay 205, conductor 237, to battery through the winding of relay 233. Relay 233, upon energizing, 30 locks through its lower armature and contact, to ground at the inner armature and front contact of relay 212. The operator, noting the display of number 0000—R, recognizes it as a test line call and inserts 35 the plug 223 into the test line jack 227, whereupon relays 228, 217 and 130 energize in series, as previously described, relays 130 and 217 performing the functions previously 40 described in connection with their operation on previous test calls. With relays 233 and 217 energized, a circuit is now established for relay 241, which may be traced over the pick-up conductor 240, the normal right contacts of relay 241, the winding of relay 241, 45 the upper armature and contact of relay 233, the innermost lower armature and front contact of relay 217, to ground at the armature and contact of relay 212. Relay 241, upon energizing, locks through the alternate contact 50 of its right armature over the circuit previously traced, to ground at the inner left armature of relay 212. A circuit is now established for applying ringing current to the conductors of the test line, which may be 55 traced from the source of ringing current 231, left winding of marginal relay 230, the upper armature and back contact of relay 232, the left armature and front contact of relay 241, the innermost lower armature and 60 front contact of relay 233, the upper armature and front contact of relay 228, the upper armature and front contact of relay 217, thence over the test line circuit as previously 65 traced, through the windings of relays 134 to 137, inclusive, in parallel, and returning

through the lower armature and front contact of relay 228, to ground at the innermost upper armature and front contact of relay 233. Relays 134 to 137 respond to this ringing current, but since the source 231 has been 70 reversely connected to the test line circuit, only the biased ringer 158 should respond. If the ringer 158 operates, the test man, recognizing that the test has progressed correctly, depresses the disconnect key 308 and 75 dismisses the call in the manner previously described.

If it is desired to test the trunk circuit for ringing the party M of a party line, the test man repeats the same operations as for the 80 previous ringing tests except that in this case the designation 0000—M is recorded on the keyboard. The circuits of the trunk and indicator now function as previously described with the exception that stations relay 525 85 only is operated. With relay 525 operated, a circuit is established from ground at the outer right armature and contact of relay 525, to conductor 553, lowermost armature and front contact of relay 205, conductor 238, and to battery through the winding of relay 232. Relay 232, upon energizing, 90 closes a locking circuit through its lower armature, to ground at the intermediate armature of relay 212. The operator, noting the display of number 0000—M, recognizes it as a test line call and inserts the plug 223 in the 95 trunk line jack 227, whereupon relays 130, 217 and 228 energize, relays 217 and 130 performing the functions previously described 100 and relay 228 closing a circuit for applying ringing current to the conductors of the test line. Since at this time ringing selection relay 232 is operated, current is applied from the ringing source 239 through the right 105 winding of relay 230, to the upper armature and front contact of relay 232, the innermost upper armature and back contact of relay 233, the lower armature and front contact of relay 228, thence over the test line circuit 110 through the windings of relays 134 to 137 in parallel, returning through the upper armature and front contact of relay 228, to ground at the innermost lower armature and 115 back contact of relay 233. Ringer 159 only should respond to this ringing current, corresponding to a party M station of a party line. If the ringer 159 operates, the test man then depresses the disconnect key 308 and 120 dismisses the call in the manner previously described.

Should it be desired to conduct a further test to determine if the trunk circuit functions correctly for ringing party W of a 125 party line, the test man operates the apparatus of the testing device in the manner previously described for the other ringing tests except that the test number 0000—W is recorded upon the keyboard. The circuits of the trunk and indicator now func-

tion as previously described except that stations relay 523 only is operated and the number 0000—W is displayed by the lamps of the indicator. Relay 523 closes a circuit 5 from ground at its outer right armature and front contact, through the left armature and back contact of relay 522, to conductor 552 for causing the operation of relay 233 in the manner previously described. Relay 233, 10 upon energizing, causes the energization of relay 241. Relay 523 also establishes a circuit for relay 232 which may be traced from ground at the inner left armature and front contact of relay 528, conductor 532, the inner left armatures and back contacts of relays 525 and 524, the inner left armature and front contact of relay 523, the right armature and back contact of relay 522, thence over conductor 553, and through the 15 winding of relay 232. The operator, recognizing the number 0000—W displayed on the indicator, to be a test line call, inserts the plug 223 in the test line jack 227, causing the operation of relays 130, 217 and 228, 20 as previously described. Since relays 232, 233 and 241 are all operated at this time, when ringing relay 228 operates ringing current is applied to the test line from the source 239 through the upper armature and 25 front contact of relay 232, the left armature and contact of relay 241, the innermost lower armature and front contact of relay 233, the upper armature and front contact of relay 228, thence over the test line circuit 30 through the windings of relays 134 to 137 in parallel, returning through the lower armature and front contact of relay 228, to ground at the innermost upper armature and front contact of relay 233. The ringer 35 160 should operate, indicating that the trunk circuit has functioned properly to ring the party W of a party line. The test man, upon hearing the ringer 160, throws the disconnect key 308 and dismisses the call. 40 When all tests of the trunk circuit are completed, the test man restores key 402 to its normal position and disconnects the testing device from the jacks 113 to 117, inclusive, by taking down the patching cords 45 to 109, whereupon all apparatus of the testing device and of the trunk circuit is restored to normal condition.

What is claimed is:

1. In a telephone exchange system in which line designations are displayed before an operator by means of a call indicator mechanism, a testing device, means for associating said testing device with an indicator mechanism to be tested, and means associated with said testing device for causing the display of any desired line designation on said indicator mechanism.
2. In a telephone exchange system in which line designations are displayed before an operator by means of a call indica- 55
3. In a telephone exchange system in which line designations are displayed before an operator by means of a call indicator mechanism, a call indicator mechanism to be tested, testing jacks associated with said call indicator mechanism, a portable testing device having connection jacks, cord circuits for interconnecting the jacks of said indicator mechanism with the jacks of said testing device, and means associated with said testing device for causing the display of any desired line designation on said indicator mechanism. 70
4. In a telephone exchange system in which line designations are displayed before an operator by means of a call indicator mechanism, a call indicator mechanism to be tested, testing jacks associated with said call indicator mechanism, power jacks having sources of electrical potential connected therewith, a portable testing device having connection jacks, cord circuits for interconnecting the jacks of said testing device with the jacks of said indicator mechanism and said power jacks, and means associated with said testing device for causing the display of any desired line designation on said indicator mechanism. 85
5. In a telephone exchange system in which line designations are displayed before an operator by means of a call indicator mechanism under the control of a central office sending device, a call indicator mechanism to be tested, a testing device, means for associating said testing device with said indicator mechanism, and means associated with said testing device for simulating the functions of said central office sending device to cause the display of any desired line designation on said indicator mechanism. 90
6. In a telephone exchange system in which line designations are displayed before an operator by means of a call indicator mechanism under the control of central office sending devices over interoffice trunks of various resistances, a call indicator mechanism to be tested, a testing device, means comprising a control circuit for associating said testing device with said indicator mechanism, means associated with said testing device for transmitting impulses over said control circuit for causing the display of any desired line designation on said indicator mechanism in simulation of the functioning of one of said central office senders, and means for changing the characteristics of said control circuit in cor- 105
- 120
- 125
- 130

- responce with the characteristics of the various trunks over which said indicator mechanism is controlled in actual service.
7. In a telephone exchange system in which line designations are displayed before an operator by means of a call indicator mechanism under the control of central office sending devices over interoffice trunks of various resistances, a call indicator mechanism to be tested, a testing device, means comprising a control circuit for associating said testing device with said indicator mechanism, means associated with said testing device for transmitting impulses over said control circuit for causing the display of any desired line designation on said indicator mechanism in simulation of the functioning of one of said central office senders, resistance elements, and keys for variously including said resistance elements in said control circuit in correspondence with the resistance of the various trunks over which said indicator mechanism is controlled in actual service.
8. In a telephone exchange system in which line designations are displayed before an operator by means of call indicator mechanism under the control of central office sending devices over interoffice trunks of various lengths, a call indicator mechanism to be tested, a testing device, means comprising a control circuit for associating said testing device with said indicator mechanism, means associated with said testing device for transmitting impulses over said control circuit for causing the display of any desired line designation on said indicator mechanism in simulation of the functioning of one of said central office senders, sources of impulsive current of different potentials, and keys for variously including said sources of current in said control circuit for simulating the operating conditions imposed upon said indicating mechanism in actual service by said various trunks.
9. In a telephone exchange system in which line designations are displayed before an operator by means of a call indicator mechanism under the control of central office sending devices over interoffice trunks of various lengths, a call indicator mechanism to be tested, a testing device, means comprising a control circuit for associating said testing device with said indicator mechanism, means associated with said testing device for transmitting impulses over said control circuit for causing the display of any desired line designation on said indicator mechanism in simulation of the functioning of one of said central office senders, resistance elements, a plurality of sources of impulsive current of different potentials, and keys for variously including said resistance elements and said sources of current in said control circuit to simulate the operating conditions imposed upon said indicator mechanism in actual service by said interoffice trunks.
10. In a telephone exchange system in which line designations are displayed before an operator by means of a call indicator mechanism under the control of a central office sending device, a call indicator mechanism to be tested, a testing device, means comprising a control circuit for associating said testing device with said indicator mechanism, means associated with said testing device for recording a line designation, and a spring driven switch for transmitting impulses over said control circuit for causing the display of said recorded designation upon said indicator mechanism.
11. In a telephone exchange system in which line designations are displayed before an operator by means of a call indicator mechanism under the control of a central office sending device, a call indicator mechanism to be tested, a testing device, means comprising a control circuit for associating said device with said indicator mechanism, a keyboard associated with said testing device upon which may be recorded the designation of any line, and a spring driven switch for transmitting impulses over said control circuit for causing the display of said recorded designation upon said indicator mechanism.
12. In a telephone exchange system in which line designations are displayed before an operator by means of a call indicator mechanism under the control of a central office sending device, a call indicator mechanism to be tested, a testing device, means comprising a control circuit for associating said testing device with said indicator mechanism, a keyboard associated with said testing device upon which may be recorded the designation of any line, a spring driven switch, and key controlled means for releasing said switch for transmitting impulses over said control circuit for causing the display of said recorded designation upon said indicator mechanism.
13. In a telephone exchange system in which line designations are displayed before an operator by means of a call indicator mechanism under the control of a central office sending device, a call indicator mechanism to be tested, a testing device, means comprising a control circuit for associating said testing device with said indicator mechanism, and a plurality of keys associated with said testing device for transmitting individual impulses of various characteristics over said control circuit for causing the display of any desired line designation upon said indicator mechanism.
14. In a telephone exchange system in which line designations are displayed before an operator by means of a call indicator hav-

- ing sensitive positively and negatively polarized control relays and a marginal control relay, a call indicator to be tested, a testing device, means comprising a control circuit 5 for associating said testing device with the controlling relays of said indicator and a plurality of keys associated with said testing device for transmitting individual impulses of strong or weak positive or negative current over said control circuit for operating 10 said relays to cause the display of any desired line designation upon said indicator.
15. In a telephone exchange system in which line designations are displayed before an operator by means of a call indicator having sensitive positively and negatively polarized control relays and a plurality of marginal control relays having different operating margins, a call indicator 20 mechanism to be tested, a testing device, means comprising control circuits for associating said testing device with the sensitive control relays and with any one of said marginal control relays of said indicator 25 mechanism, means for transmitting impulses over any one of said control circuits for causing the operation of said control relays to govern the display of any desired line designation upon said indicator mechanism, 30 and means for selecting one of said control circuits.
16. In a telephone exchange system in which line designations are displayed before an operator by means of a call indicator 35 having sensitive positively and negatively polarized control relays and a plurality of marginal control relays having different operating margins, a call indicator mechanism to be tested, a testing device, a plurality 40 of control circuits for associating said testing device with said indicator mechanism, each of said control circuits extending through said sensitive control relays and one of said marginal relays, means for transmitting impulses over any one of said control 45 circuits for causing the operation of said control relays to govern the display of any desired line designation, and switching means for selecting one of said control circuits.
50. 17. In a telephone exchange system in which line designations are displayed before an operator by means of a call indicator having sensitive positively and negatively polarized control relays, a call indicator mechanism to be tested, a testing device, means comprising a control circuit for associating said testing device with the control 55 relays of said indicator mechanism, and means at said testing device for testing the 60 adjustment of either of said relays.
18. In a telephone exchange system in which line designations are displayed before an operator by means of a call indicator 65 having sensitive positively and negatively polarized control relays, a call indicator mechanism to be tested, a testing device, means comprising a control circuit for associating said testing device with the control relays of said indicator mechanism, a key for including said resistance element, a key for including said resistance element in said control circuit, and means for transmitting individual positive or negative impulses over said control circuit for testing the adjustment of either 70 of said relays.
19. In a telephone exchange system in which line designations are displayed before an operator by means of a call indicator which is provided with a group of relays for 80 automatically controlling the selection of the ringing current to be applied to a called subscriber's line in accordance with the stations digit of the line designation, a call indicator mechanism to be tested, a testing device, means for associating said testing device with said indicator mechanism, means for transmitting impulses to said indicator mechanism to cause the display of a line designation thereon, and means at said testing 85 device for checking the accuracy with which said relays function.
20. In a telephone exchange system in which line designations are displayed before an operator by means of a call indicator 90 which is provided with a group of relays for automatically controlling the selection of the ringing current to be applied to a called subscriber's line in accordance with the stations digit of the line designation, a call 95 indicator mechanism to be tested, a testing device, means for associating said testing device with said indicator mechanism, means for transmitting impulses to said indicator mechanism for displaying the designation 100 of any line thereon, a plurality of relays at said testing device under control of the relays of said group, and signals operated conjointly by the relays of said testing device 105 for indicating the accuracy with which said indicator mechanism functions for ringing current selection.
21. In a telephone exchange system in which connections are extended manually in accordance with called line designations displayed before an operator by means of a call indicator mechanism, an operator's trunk circuit to be tested, testing jacks associated with said trunk circuit, a portable testing device having connection jacks, cord 110 circuits for interconnecting the jacks of said testing device with the jacks of said trunk circuit, an indicator mechanism associated with said trunk circuit, and means at said testing device for causing the operation of said trunk circuit and said indicator mechanism in simulation of actual service conditions.
22. In a telephone exchange system in which connections are extended manually in 115

- accordance with called line designations displayed before an operator by means of a call indicator mechanism, an operator's trunk circuit to be tested, a call indicator mechanism for association with said trunk circuit, a test line, a testing device, means for connecting said testing device with said trunk circuit and with said test line means associated with said testing device for 5 causing the display of the designation of said test line on said indicator, means at said trunk circuit responsive to the connection thereof with said test line for applying ringing current to said test line, a calling bell on said test line, responsive to said ringing current, and means at said testing device for tripping said ringing current and for indicating whether the ringing current has been successfully tripped. 10
23. In a telephone exchange system, an operator's trunk circuit to be tested, a supervisory relay for said trunk circuit, a test line to which said trunk circuit may be connected, a testing device, means for connecting said testing device with said trunk circuit and with said test line, a relay at said testing device under the control of said supervisory relay, a signal controllable by the relay of said testing device, means at 15 said testing device for causing the energization and release of said supervisory relay, and means including said signal for checking the operation of said supervisory relay. 20
24. In a telephone exchange system, an operator's trunk circuit to be tested, a supervisory relay for said trunk circuit, a test line to which said trunk circuit may be connected, a testing device, means for connecting said testing device with said 25 trunk circuit and with said test line, a relay at said testing device under the control of said supervisory relay, a signal lamp controllable by the relay of said testing device, means at said testing device for repeatedly causing the energization and release of said supervisory relay, and a matching lamp controlled by said latter means, said lamps when extinguished and lighted in unison serving as an indication 30 that said supervisory relay functions correctly. 45
25. In a telephone exchange system, an operator's trunk circuit to be tested, a supervisory relay for said trunk circuit, a test line to which said trunk circuit may be connected, a testing device, means for connecting said testing device with said trunk circuit and with said test line, a relay at said testing device under the control of said 50 supervisory relay, a signal lamp controllable by the relay of said testing device, a switch at said testing device for applying strong operating current to said supervisory relay for thereafter reducing the 55 strength of said current to a value which should cause the release of said supervisory relay and for then increasing said current to a value which should cause the energization of said supervisory relay, and a matching lamp controlled by said switch, said lamps when extinguished and lighted in unison serving as an indication that said supervisory relay is properly adjusted for 60 operation. 70
26. In a telephone exchange system, an operator's trunk circuit to be tested, a supervisory relay for said trunk circuit, a test line to which said trunk circuit may be connected, a testing device, means for connecting said testing device with said trunk circuit and with said test line, a relay at said testing device under the control of said supervisory relay, a signal lamp controllable by the relay of said testing device, a switch at said testing device for applying strong current for saturating said supervisory relay for a definite period, for thereafter reducing the strength of said current for a definite period to a value which should cause the release of said supervisory relay and for then increasing the strength of current for a further definite period to a value which should be just sufficient to cause the energization of said supervisory relay, and a matching lamp controlled by said switch, said lamps when extinguished and lighted in unison serving as an indication that said supervisory relay is properly adjusted for 75 80 85 90 95 100 105 110 115 120 125 130 operation. 135
27. In a telephone exchange system, an operator's trunk circuit to be tested, a supervisory relay for said trunk circuit, a test line to which said trunk circuit may be connected, a testing device, means for connecting said testing device with said trunk circuit and with said test line, a relay at said testing device under the control of said supervisory relay, a signal lamp controllable by the relay of said testing device, resistance elements in said test line in circuit with said supervisory relay, a switch at said testing device for short-circuiting a plurality of said resistance elements to apply strong saturating current to said supervisory relay, for thereafter removing said short circuit to decrease said current to a value which should cause the release of said supervisory relay and for then short-circuiting another plurality of said resistance elements for increasing said current to a value just sufficient for causing the energization of said supervisory relay, and a matching lamp controlled by said switch, said lamps when extinguished and lighted in unison serving as an indication that said supervisory relay is properly adjusted for operation. 140
28. In a telephone exchange system, an operator's trunk circuit to be tested, a supervisory relay for said trunk circuit, a test line to which said trunk circuit may be con- 145 150 155 160 165 170 175 180 185 190 195 200

nnected, a testing device, means for connecting said testing device with said trunk circuit and with said test line, a relay at said testing device under the control of said supervisory relay, a signal lamp controllable by the relay of said testing device, adjustable resistances in said test line in circuit with said supervisory relay whereby the strength of the current flowing through said supervisory relay may be fixed for certain operating and no-operating limits, a key at said testing device for applying strong saturating current to said supervisory relay and for reducing said current to the non-operating value fixed by said adjustable resistances, and a key for increasing said current to the operating value fixed by said adjustable resistances, said lamp indicating when the adjustment of said supervisory relay is such as to enable it to function correctly upon the successive operation of said keys.

29. In a telephone exchange system, an operator's trunk circuit to be tested, sources of ringing current, means for selectively applying current from said sources to the strands of said trunk circuit, a test line to which said trunk circuit may be extended, ringers on said test line selectively responsive to said sources of ringing current, a testing device, means for associating said testing device with said test line, and means at said testing device for tripping said ringing current.

30. In a telephone exchange system, an operator's trunk circuit to be tested, sources

of ringing current, automatically operated means for selectively applying current from said sources to the strands of said trunk circuit, a test line to which said trunk circuit may be extended, ringers on said test line selectively responsive to said sources of ringing current, means for connecting a low resistance bridge across said test line for tripping said ringing current, a testing device, and means at said testing device for controlling said first named means.

31. In a telephone exchange system, an operator's trunk circuit to be tested, a call indicator mechanism associated therewith, a testing device, means for connecting said testing device with said trunk circuit, means at said testing device for recording upon said indicator mechanism the designation of any party line subscriber's station, sources of ringing current at said trunk circuit, means under the control of said indicator for selectively applying said sources of current to the strands of said trunk circuit in accordance with the stations designations recorded upon said indicator mechanism, a test line to which said trunk circuit may be connected, and ringers on said test line selectively responsive to said sources of ringing current whereby the accuracy with which said ringing current selection means function, may be checked.

In witness whereof, I hereunto subscribe my name this 30th day of October, A. D. 1922.

ARNOLD S. BERTELS.
